(57) **ABSTRACT**

A new and distinct Impatiens plant named 'HGI-1033-3' characterized by having a typical compact growth, small flowers and a unique soft pink color for mini type Impatiens.

2 Drawing Sheets

1

Latin name of the genus and species of the plant claimed:
Impatiens walleriana.

Variety denomination: HGI-1033-3.

BACKGROUND OF THE INVENTION

The present invention relates to a new and distinct cultivar of Impatiens plant, botanically known as *Impatiens walleriana*, and hereinafter referred to by the cultivar name 'HGI-1033-3'.

The new cultivar originated from a cross made in a controlled breeding program in the village of Hem, the Netherlands. The female parent is 'IB-1-1' (unpatented). The male parent is 'IB-10-2' (unpatented). 'HGI-1033-3' was discovered and selected by the inventor, in November 1999, as a flowering plant within the progeny of the stated cross in a controlled environment in the village of Hem, the Netherlands.

'HGI-1033-3' is a product of a planned breeding program conducted by the inventor and selected in a controlled cultivated environment in the village of Hem, the Netherlands. Asexual reproduction of the new cultivar by vegetative cuttings used in propagation was first performed in December 1999 in the village of Hem, the Netherlands and has demonstrated that the combination of characteristics as herein disclosed for the new cultivar are firmly fixed and reproduce true to type in successive generations of asexual reproduction.

BRIEF DESCRIPTION OF THE INVENTION

The following traits have been repeatedly observed and are determined to be basic characteristics of 'HGI-1033-3' which in combination distinguish this Impatiens as a new and distinct cultivar:

1. Compact growth;
2. Small flowering;
3. Small leaves; and
4. A unique in dwarf flowering mini type *Impatiens walleriana*.

'HGI-1033-3' has not been observed under all possible environmental conditions. The phenotype of the new cultivar may vary significantly with variations in environment such as temperature, light intensity, and daylength without any change in the genotype of the plant. The following observations, measurements and values describe the new

2

cultivar as grown in the Village of Hem, the Netherlands under conditions which closely approximate those generally used in commercial practice.

Of the many commercial cultivars known to the present 5 inventor, the most similar in comparison to 'HGI-1033-3' is the cultivar 'Firefly Lavender'. The overall habit and appearance of 'HGI-1033-3' and 'Firefly Lavender' are comparable, however 'HGI-1033-3' has a more compact growth, the flowers are slightly larger, and the flower color 10 of 'Firefly Lavender' is RHS N74B.

In comparison to the instant plant, both parental cultivars have a more vigorous plant habit. When grown under the same conditions in a greenhouse as potted plants, the parental cultivars are 50% taller than 'HGI-1033-3'. The flower 15 color of parental cultivars differ from 'HGI-1033-3'. Flowers of the female parental cultivar are RHS 155A; flowers of the male parental cultivar are RHS 43C and are larger, 4–5 cm in diameter.

BRIEF DESCRIPTION OF THE DRAWING

The accompanying photographic illustrations show typical characteristics of Impatiens 'HGI-1033-3', with colors being as true as possible with illustrations of this type.

20 The first drawing shows the plant in its entirety, with compact growth and numerous flowers.

25 The second drawing shows an enlargement of one typical flower.

DETAILED BOTANICAL DESCRIPTION

30 The following observations, measurements and values describe the new cultivar as grown in the village of Hem, the Netherlands, under conditions which closely approximate those generally used in commercial practice. The plant 35 grows well under normal greenhouse conditions, however the temperature should not decrease below 15 degrees Centigrade. Shading of the plants in high light conditions is essential. Color references are made to The Royal Horticultural Society Colour Chart (R.H.S.), except where general 40 colors of ordinary significance are used. Color values were taken under daylight conditions at approximately noon in the village of Hem, the Netherlands.

Parentage:

45 Female parent.—IB-1-1.

Male parent.—IB-10-2.

Propagation:

Type cutting.—Stem cutting.

Time to initiate roots.—10 to 12 days at an average of 22 degrees Centigrade.

Time to develop roots.—18 to 21 days at an average of 21 degrees Centigrade.

Rooting habit.—Fibrous, branching and fine roots.

Plant: General Appearance and Form:

Height.—Average 8 centimeters, depending on cultivation conditions and when growing in a pot of 10 centimeters wide.

Width.—Average 10 centimeters, depending on cultivation conditions.

Growth and branching habit.—Upright and freely branching.

Flowering response.—Day length neutral.

Flowering season.—Year-round in controlled climate conditions; outdoors until start of frost period.

Winter hardiness.—No.

Lastingness of the individual bloom.—5 to 7 days depending on temperature of the environment.

Crop time.—6 weeks from cutting to plant.

Fragrance.—None.

Foliation:

Overall shape of leaf.—Lanceolate to elliptic. *Base*: Acute. *Tip*: Acute.

Margin.—Crenate with ciliation.

Texture.—Soft.

Main color of upper surface.—Mature leaf: RHS 137B. Immature leaf: RHS 137B.

Main color of lower surface.—Mature leaf: RHS 138B. Immature leaf: RHS 138B.

Venation color.—Upper surface: Pinnate RHS 137B. Lower surface: RHS 137B.

Size.—Length: 4 centimeters. Width: 2.5 centimeters.

Leaf base shape.—Acute.

Leaf apex shape.—Acute.

Petiole.—Length: 2 centimeters. Diameter: 0.2 centimeters. Color: RHS 146C.

Flower description:

Flower type and habit.—Single, placed in upper leaf axils.

Flowering season.—Year-round in controlled climate conditions; outdoors until start of frost period.

Flower Size: 3 cm long; 2.5 cm wide. *Average Number*: 2 to 7 per leaf axil, large numbers per plant.

Height: 3 centimeters. *Petals*: *Number/Arrangement*: 5, arranged around the stamen. *Length*: 1.7 centimeters. *Width*: 0.9 centimeters. *Shape*: Upper petal round, the remaining 4 oval shaped. *Margin*: Sharp. *Texture*: Soft. *Color*: Upper surface: RHS N74C, the center of the two lower petals RHS 155C. Lower surface: RHS 75B.

Stem.—Average length: 1.5 centimeters depending on cultivation conditions. *Average diameter*: 15 millimeters. *Color*: RHS 138A.

Spur.—Length: 2 cm. *Color*: RHS 155C.

Bud.—*Response*: Daylight neutral. *Color*: RHS 155C to RHS 75B just before opening. *Size before opening*: 0.5 centimeter. *Pedicel Length*: Stretching to 2 centimeters. *Pedicel Color*: RHS 138A.

Reproductive organs:

Stamen.—1, RHS 147B.

Seed development.—No observations to date.

Fruit.—No observations to date.

Anthers.—Caps over pistil, drops off when flower mature, color RHS 141B.

Pollen.—No observations to date.

Stigma.—Star-shaped when opened, color RHS 155B.

Ovary.—Oval shape, color RHS 141B.

Disease resistance: No observations to date.

I claim:

1. A new and distinct *Impatiens* plant named 'HGI-1033-3', substantially as illustrated and described herein.
